UNITED STATES PATENT OFFICE

144,066

DESIGN FOR A DAVENPORT

Frederick T. Paden, United States Army,
Collingswood, N. J.

Application May 25, 1945, Serial No. 119,711

Term of patent 7 years

(Cl. D15—11)

To all whom it may concern:

Be it known that I, Frederick T. Paden, a citizen of the United States, residing at Collingswood, in the county of Camden and State of New Jersey, have invented a new, original, and ornamental Design for a Davenport, of which the following is a specification, reference being had to the accompanying drawings, forming a part hereof.

Fig. 1 is a front elevational view of a davenport showing my new design.

Fig. 2 is a top view thereof with a portion of

the davenport cut away to illustrate certain features thereof the dotted lines shown in the other drawings figures being omitted.

Fig. 3 is a rear elevational view thereof.

Fig. 4 is a side elevation thereof.

Fig. 5 is a top perspective view thereof.

The characteristic features of my design are shown by means of full lines in the drawings.

I claim:

The ornamental design for a davenport, as shown and described.

FREDERICK T. PADEN.
